Patented June 16, 1914.

UNITED STATES PATENT OFFICE.

JOHN O'TOOLE, OF LOS ANGELES, CALIFORNIA.

PUZZLE.

1,100,026.

Specification of Letters Patent. Patented June 16, 1914.

Application filed July 30, 1913. Serial No. 781,984.

To all whom it may concern:

Be it known that I, JOHN O'TOOLE, a citizen of the United States, residing at Los Angeles, in the county of Los Angeles, State 5 of California, have invented a new and useful Improvement in Puzzles, of which the following is a specification.

My invention relates to puzzles having educational features, and the object of my 10 invention is to provide a puzzle instructive of the use and the geographical location of the Panama Canal, the location of the principal seaports of the world and the connecting lines of travel between the seaports of 15 the Atlantic Ocean and those of the Pacific Ocean through the canal.

In the drawings—Figure 1 is a map of the world in projection, showing the location of the canal, the seaports and the connecting lines of travel. Fig. 2 is one of the 20 blocks used to represent boats, and is colored red. Fig. 3 is the same as Fig. 2 and is colored blue.

Referring to the drawings in detail—The 25 canal, which is the center of the puzzle, is represented by the circle 1 in Fig. 1. The seaports on the Atlantic side are represented by the circles 2 and are connected in the different routes and with the canal by the 30 lines of travel 4. The seaports on the Pacific side are represented by the circles 3 and are connected in the different routes and with the canal by the lines of travel 5.

The circle 1, Fig. 1, being the center of 35 the puzzle, the number of seaports 2 and 3 are each the same. A boat is placed at each port with the bow or pointed end turned inwardly toward the canal, the red boats as in Fig. 2 being placed at ports 3 and the blue 40 boats as in Fig. 3 at ports 2. The circle 1, being vacant, leaves an extra port.

The problem is to change the boats from 45 side to side through the canal by using the extra port, so that boats 2 will rest at ports 2 and boats 3 at ports 3. This is accomplished by moving the boats forward one space or jumping one opposing boat at a time.

While in transit the boats of each color 50 are separated from each other by an opposing boat or the vacant port. Commencing with the line of travel 4 leading north from the canal along the east coast of North America and the line of travel 5 leading 55 south along the west coast of South America by moving the nearest boat on line 5 to

the canal and jumping the nearest boat on line 4 over it to the vacant port on line 5. Move the boat from the port on the branch line of line 4 to the vacant port and jump 60 the boat from the canal to the port thus vacated. Jump the red boat from the second port on line 5 to the canal and move the one from the third to the second. Jump the blue boats from the first port on line 5 to 65 the third and from the first port on line 4 to the first port on line 5 move the boat from the second port on line 4 to the first. Jump the red boat from the canal to the second port. Jump from the second port 70 on line 5 to the canal and from the fourth to the second. Move the blue boat from the third port on line 5 to the fourth and jump from the first to the third. Jump from the first port on line 4 to the first on 75 line 5 and from the third port on line 4 to the first. Move from the fourth port to the third. Jump the red boat from the second port to the fourth and from the canal to the second. Jump from the second port on line 80 5 to the canal and move the blue boat from the first port to the second. Jump from the first port on line 5 to the first on line 4, from the third to the first and from the fifth to the third on line 4, move from the sixth 85 port to the fifth. Jump the red boats from the fourth to the sixth, from the second to the fourth and from the canal to the second port. Move a red boat from the nearest port on one of the other lines 5 to the canal 90 and jump the blue boats forward as before. By jumping the sides alternately in this manner, moving one forward before the opposite side is started to jump, they are changed from side to side of the canal and 95 boats 2 are resting at ports 2 and boats 3 at ports 3.

The puzzle may be applied to any form of map, the number of seaports increased or diminished or constructed in any suitable 100 shape or manner without departing from the spirit of my invention as set up in the following claims.

I claim—

1. A puzzle consisting of a map of the 105 world, a spot showing the location of the Panama Canal, spots showing the location of the principal sea ports of the world, one half the number on the eastern side and one half on the western side of the canal, lines 110 showing routes of travel and connecting the sea ports with the canal, blocks of different

colors representing boats placed at all the ports, blocks of one color being placed on the eastern side and those of another color being placed on the western side, and adapted to be moved and jumped from spot to spot and from side to side of the canal.

2. A puzzle consisting of a map of one central spot, of two groups of spots of an equal number each, one group being on each side of the center, lines connecting the

groups of spots with the center, blocks of different colors placed on all of the spots but the center, the different colors being placed on the different sides and adapted to be moved and jumped from spot to spot and from side to side of the center. 15

JOHN O'TOOLE.
